WITNESS:

BY *Victor J. Evans*

ATTORNEY

UNITED STATES PATENT OFFICE.

JAMES E. ELMER, OF PRESCOTT, ARIZONA.

PENCIL HOLDER.

Application filed November 27, 1922. Serial No. 603,652.

To all whom it may concern:

Be it known that I, JAMES E. ELMER, a citizen of the United States, residing at Prescott, in the county of Yavapai and State 5 of Arizona, have invented new and useful Improvements in Pencil Holders, of which the following is a specification.

My invention relates to holders for retaining pencils, pens and analogous articles 10 against accidental displacement, and comprising a clip to engage the upper edge of the pocket or like part, and one or more receivers for the pencil or like article to be retained thereby.

15 The invention provides a device of this character which facilitates the placing of the article in the receiver and which prevents the casual displacement thereof, the ends of the receivers being outwardly flared to direct the 20 article therein.

The objects and advantages will be apparent and suggest themselves as the nature of the invention is understood.

25 While the drawing illustrates an embodiment of the invention, it is to be understood that in adapting the same to meet the different conditions and requirements, various changes in form, and minor details of construction may be resorted to without departing 30 from the nature of the invention.

Referring to the accompanying drawing forming a part of the specification:—

Figure 1 is a perspective view of the invention mounted in place upon the pocket of 35 a garment.

Figure 2 is a side elevation thereof.

Figure 3 is a perspective view thereof.

Figure 4 is a top elevation.

Referring to the drawing in detail 1 represents a portion of a garment, of which 2 indicates the hem or upper edge of a pocket to which my holder is attached by the lever clasp 3. The body 4 is preferably formed of 40 an integral piece of sheet metal which is cut and bent to form intermediate and end cylindrical sections or sleeves 5 for the reception of the pencil or like article. A connect-

ing web 6 is thusly formed and provided with an upwardly extending portion 7 which is then bent downwardly to provide a wing 50 or plate 8 to which is pivoted the clamping lever 9 which is provided with resilient extensions 10 that produce the necessary tension upon the lever 9 by contact with the web 6, the lever 9 is also provided with an inwardly projecting penetrating tongue 11 at its free end which engages a similar tongue 12 struck from the intermediate sleeve 5 when the holder is applied to the garment and binds the fabric there between which 60 produces an effective fastening element which is capable of preventing displacement of the holder.

A pencil holder such as described is simple and can be produced very cheaply as the entire device is formed of a single plate of sheet metal cut to proper shape and the parts folded to form the sleeves 5 the web 6, and extension 7 to which the clamping lever is attached. These folds and retaining elements may be made without the use of expensive machinery and produced with great rapidity. The sleeves 5 are the only part exposed to view and this may be ornamented and made attractive as is desired.

Having described my invention, what I claim and desire to secure by Letters Patent, is:—

A pencil holder of the class described, consisting of a single piece of metal cut to form 80 integral resilient sleeves having a connecting web therebetween, a portion of said web being directed to form a back wing, a clamping lever pivoted to said wing and having resilient tongues directed therefrom to produce tension upon said lever by engaging said web, and an inwardly direct penetrating tongue upon the free end of said lever, a similar tongue struck from the back wall of the intermediate sleeve and cooperating with 85 the first mentioned tongue to bind the fabric therebetween when the holder is applied.

In testimony whereof I affix my signature.

JAMES E. ELMER.
